CLAIM

The ornamental design for a bottle with handle, as shown and described.

DESCRIPTION

FIG. 1 is a perspective view of a bottle with handle, embodying our new design;
 FIG. 2 is a front elevational view thereof, the back elevational view thereof being a mirror image;
 FIG. 3 is a left side elevational view thereof;
 FIG. 4 is a right side elevational view thereof; and,
 FIG. 5 is a top view thereof.

The broken lines shown in the figures are for illustrative purposes only, and form no part of the claimed invention.
